Attn:

UNITED STATES PATENT OFFICE.

JAFEW S. VAN BUREN, OF ALBANY, NEW YORK, ASSIGNOR TO RATHBONE, SARD & CO., OF SAME PLACE.

DESIGN FOR A STOVE.

SPECIFICATION forming part of Design No. 21,100, dated October 6, 1891.

Application filed August 1, 1891. Serial No. 401,405. Term of patent 3½ years.

To all whom it may concern:

Be it known that I, JAFEW S. VAN BUREN, of Albany, in the county of Albany and State of New York, have invented certain new and 5 useful Improvements in Designs for Stoves; and I do hereby declare the following to be a full, clear, and exact description of the invention, such as will enable others skilled in the art to which it pertains to make and use it, 10 reference being had to the accompanying drawing, which forms part of this specification.

My invention has relation to a new and original design for stoves, of which the following is a specification, reference being had to the accompanying drawing, forming a part thereof.

The accompanying drawing is a perspective view of my new and original design for a 20 stove complete.

The ornamental top of the design consists of the rectangular cover *a*, having a curved front, which is placed upon and supported by a vertical series of short flutes *d*, which 25 are placed over and supported upon a downwardly and outwardly curved portion *b*. The portion *a* is preferably, though not necessarily, provided with an urn or other suitable ornament *C*, which furnishes a finish for the 30 top thereof, and this portion *a* and the outwardly and downwardly curved section *b*, which is immediately below the short vertically-fluted portion *d*, are both provided with a suitable scroll ornamentation, as shown.

Placed immediately below this section *b* is a 35 section which is provided with outwardly and forwardly curved front corners *D*, which are provided between them with an arch, as shown, and these corners and the arch are 40 ornamented by appropriate scroll-work, as shown. This section, having the said corners *D*, is just above the upper dome portion of the stove, which is provided with downwardly and radially curved flutes *G* immediately below the said section, both in front and at the sides.

This dome portion is provided with a series 45 of mica doors *b*, as shown, the divisions *H* of which are provided with longitudinal beads. Below the series of mica doors *b* is a second 50 series of mica doors *I*, which have the divisions thereof provided with longitudinal heads, and these divisions support a scroll-work *J*,

which branch outward from the center thereof, as shown. Another series of mica doors *K* are just below the upper and larger series 55 *I*, and are separated therefrom by an annular or circular bead *M*, as shown, and the divisions of these doors are also provided with longitudinal beads, and the division-bars of these doors *K* are further decorated by means of 60 scroll-work *L*, which extends from the upper center thereof to the lower diagonal corners of the said section. Below the series of mica doors *K* is a hearth *N*, which extends outward and is slightly curved downward, and 65 which hearth is nickelized and provided with a suitable ornamental design. Directly below the hearth is an ash-pit *O*, which is suitably decorated and provided with the arched draft-openings *Q*, and a register *P*, which is provided with ornamentations which show through the said draft-openings, as illustrated. This 70 ash-pit rests upon a downwardly and outwardly curved section *R*, which also forms a part of the ash-pit, and which is suitably decorated with any desired design, and below this section is the base *S*. This base is provided with the gracefully-curved lines *V*, which extend from the middle of the front and sides of the base upon and form a part 75 of the supporting-legs *W*. This is preferably, though not necessarily, decorated by means of any desired design above the curved lines *V*.

Having thus described my design, what I 85 desire to secure by Letters Patent is—

1. A design for a stove, substantially as herein shown and described.
2. A design for an upper section of a stove, substantially as herein shown and described. 90
3. A design for a mica section of a stove, substantially as herein shown and described.
4. A design for a base-section of a stove, substantially as herein shown and described.
5. A design for a supporting-base for a 95 stove, substantially as herein shown and described.

In testimony whereof I affix my signature in presence of two witnesses.

JAFEW S. VAN BUREN.
